UNITED STATES PATENT OFFICE.

ISAAC F. RUBEL, OF CHICAGO, ILLINOIS.

DESIGN FOR A KNIFE-HANDLE.

SPECIFICATION forming part of Design No. 16,686, dated May 11, 1886.

Application filed March 22, 1886. Serial No. 196,129. Term of patent 3½ years.

To all whom it may concern:

Be it known that I, ISAAC F. RUBEL, a citizen of the United States, residing at Chicago, in the county of Cook and State of Illinois, have invented and produced a certain new and original Design for Knife-Handles, of which the following is a specification, reference being had to the accompanying drawing, forming a part thereof, said drawing being a side view of a knife whose handle contains my design.

A is the scale or side plate of the handle. B is the bolster. C is the tip.

My design relates to the ornamentation of a knife-handle, and comprises upon the lateral surfaces of the same the terminal parts B and C and the intermediate part, A, which is provided with the terminal projections A' at one end, and A'' A''' at the other end, protruding into the terminal parts B and C, respectively. The form of these projections is the essential characteristic of my design. The projection A' is shaped in the form of a human head and face seen in profile. The projections A'' A''' are each shaped in a conventional form of a human foot and ankle, with the toes of both feet turned outward. The body or main por-

tion of the intermediate part, A, is shaped to bear a general resemblance to the outline of a human figure draped from the shoulders to the ankles, so that the entire outline of the intermediate part, A, with its projections, bears a resemblance to an entire human figure draped from the shoulders in a long cloak, the head being turned to one side to show the face in profile.

I claim—

The design for a knife-handle herein shown and described, comprising the terminal parts B and C and the intermediate part, A, having the projections protruding into the terminal parts, the projection at one end being in the outline of a human face seen in profile, and the projections at the other end being in the conventional outline of human feet.

In testimony whereof I have hereunto set my hand, in the presence of two witnesses, at Chicago, Illinois, this 9th day of March, A. D. 1886.

ISAAC F. RUBEL.
